UNITED STATES PATENT OFFICE

SVEN LEOPOLD BENGTSON, OF LONDON, ENGLAND, ASSIGNOR TO MORGAN CONSTRUCTION COMPANY, OF WORCESTER, MASSACHUSETTS, A CORPORATION OF MASSACHUSETTS

GAS PRODUCER

Application filed July 24, 1929. Serial No. 391,462.

The present invention relates to gas producers, and more particularly to a means for automatically securing, at regular predetermined intervals, the discharge of ashes from the bottom of the producer body by a plowing device, which is made operative during a portion of each revolution of the producer. Other objects and features of the invention are set forth more specifically hereinafter, reference being had to the accompanying drawings, in which—

Fig. 1 is a vertical sectional view of a rotary gas producer of conventional construction, having my invention applied thereto.

Fig. 2 is a top plan view illustrating the parts shown in Fig. 1, and other parts of the invention.

Fig. 3 is a fragmentary detail view, on an enlarged scale, showing certain parts as viewed from the left hand side of Fig. 2.

Like reference characters refer to like parts in the different figures.

Referring first to Fig. 1, the numeral 1 indicates the fuel-containing shell of the gas producer, said shell being here shown as supported in spaced relation to an ash and water seal pan 2 by means of arms 3, 3 that radiate from a hollow support 3' at the center of said ash pan. Said support 3' registers with the usual central blast passage 3" of the producer, and the arms 3, 3 are made hollow, to receive the blast from the central support 3' and to distribute it through their perforations 3'a to the fuel bed but only one perforation is shown. Said ash pan 2 is rotatably supported on a series of rollers 4, 4 (only one being shown) and the drive for said pan, to impart rotation thereto and to the shell 1 supported thereby, is obtained from a bevel pinion 5 on a shaft 6, said bevel pinion 5 meshing with a bevel gear 7 on the bottom of said pan. An annular skirt 8, depending from the shell 1, makes a seal with the water in pan 2 to prevent the escape of gases from the bottom portion of the gas producer, and a similar water seal at the upper part of the gas producer is formed, as shown at 9, between the rotary shell 1 and a depending annular skirt 10 provided by the stationary cover or top 11 of the producer, said top or

cover 11 being supported in the usual fashion by a plurality of posts or columns 12, of which only one is shown.

Notwithstanding the unitary connection between shell 1 and pan 2, this construction leaves between these parts an unobstructed space for the operation of an ash plow 13, best shown in Fig. 2, said plow being journalled at the center of the ash pan 2 and being adapted normally to rotate in unison with said ash pan by its frictional engagement with the bottom thereof, and by the pressure thereon of the superposed rotating mass of ashes, substantially as set forth and described in the United States Letters Patent to Jefferies No. 1,198,037, dated September 12, 1916. In the producer of said Jefferies patent, provision is made for manually setting in operation certain mechanism for interposing a stop in the path of the ash plow, thereby to hold said plow stationary while the ash pan continues to rotate, and to crowd the ashes against the curved edge of the stationary plow; this crowding action forces the ashes outwardly toward the circumference of the ash pan and causes them to ride up the inclined surface of the pan's rim, for discharge from the pan at that point.

In the gas producer of the present invention, as distinguished from the gas producer of the aforesaid Jefferies patent, the need for manual intervention, to secure the operation of the ash plow, is wholly eliminated; instead, provision is made for automatically procuring the operation of said plow at suitable intervals, so that, once the mechanism is properly adjusted, no further attention, on the part of the operator to the operation of the ash plow during a run of the producer, is required. The mechanism for accomplishing this result will now be described.

Referring to Figs. 2 and 3, the shaft 6 which carries the driving pinion 5 employed to rotate the gas producer, is driven at a relatively slow speed through a train of reduction gearing 14, from any suitable source of power, and on one of the countershafts of this reduction gearing is mounted an eccentric 15. The motion of said eccentric 15 is transmitted through a connecting rod 16, so

as to secure oscillation of a bell crank lever 17, fulcrumed at 18 on a supporting standard 19, and this motion of the bell crank 17 is transmitted by a link 20 to a rocker arm 21 pivoted on a stud 22 that projects outwardly from one of the posts or columns 12. Revolvably mounted on said stud 22 is a cam 23, having secured thereto concentrically a ratchet wheel 24. A pawl 25 pivoted to the rocker arm 21 is so disposed as to operatively engage the teeth of ratchet wheel 24 when the link 20 draws the rocker arm 21 to the left in Fig. 3, thereby to give the cam 23 a small angular movement in a counterclockwise direction at each revolution of the shaft of eccentric 15. A holding pawl 26 prevents retrograde movement of cam 23 on the right hand swing of rocker arm 21, and on this right hand swing, the pawl 25 is dragged over the teeth of ratchet wheel 24 without effect. The gearing and ratchet mechanism are so arranged that the pan 2 will make one revolution in slightly less time than the cam 23.

As best shown in Figs. 1 and 2, the plow 13 near its free end carries an upwardly inclined portion 27 for scraping action upon the rim of pan 2, and this portion 27 terminates in a bar 28 which projects over the rim of said pan. As best shown in Fig. 3, the same post or column 12 which carries the ratchet-operated cam 23, also provides a suitable bearing for a rock-shaft 29, on the inner end of which is carried a latch or hook 30, adjacent the path of plow-bar 28. An arm 31 on the other end of rock-shaft 29 carries a weight 32, whose tendency is to maintain the latch or hook 30 in lowered position, where it will intercept the plow-bar 28. A link 33 connects the arm 31 with a rocker-arm 34, pivoted at 35 and carrying a roller 36 that rides on the periphery of cam 23. The operation is as follows:

The constant uniform rotation of pan 2 carries the plow 13 around, and the plow-bar 28 contacts with the depressed latch 30 just before the raised portion or projection 37 of cam 23 arrives below the roller 36. In consequence, the plow 13 is held stationary for a short period while the pan 2 continues to rotate,—this producing a plowing action that crowds the ashes outwardly and up the surface of the blade 27, for discharge over the rim of pan 2. Such plowing, however, is only of short duration, for almost immediately the raised portion 37 of cam 23 arrives beneath the roller 36 and thereby raises the latch 30. This removes the obstruction to the rotation of plow 13, allowing the latter to resume such rotation in unison with the pan 2 which, of course, discontinues the plowing action. After the plow bar 28 has moved beyond latch 30, said latch again drops down into operative position, due to the passage of cam portion 37 down beyond the roller 36, but nevertheless, the plowing is not resumed

until a full revolution of pan 2 has taken place, to bring the plow bar 28 once more into contact with the depressed latch 30; then, as before, the plowing period of relatively short duration ensues. In this way, there is automatically obtained, at each revolution of the ash pan, a short period of ash plowing, the duration of which, manifestly, may be readily varied and adjusted to suit the rate of combustion and ash-formation within the producer, as for example by means for varying the stroke of the pawl 25 or by the use of several ratchet wheels having a different number of teeth and a corresponding number of pawls, each engaging its own ratchet wheel.

I claim:

In a gas producer, a fuel shell and an ash pan connected for rotation in unison, means for rotating said parts in the operation of the producer, an ash plow on the bottom of said pan and normally rotatable with said pan by the friction and pressure of the contained bed of fuel, a latch supported independently of said rotating shell and pan in position to engage said plow and hold it from rotation, thereby to effect removal of ashes from said pan during each engagement of said latch with said plow, a counterweight operative on said latch to hold it in the path of said plow, a rotary cam having a projection thereon adapted to raise said latch, once in each revolution of said cam, into inoperative position, thereby to release said plow for rotation in unison with said pan, means for rotating said cam at a speed slightly lower than that of said shell and pan, and means for causing the engagement of said plow with said latch to precede slightly the engagement of said cam projection with said latch, whereby in the operation of the producer, said plow is held stationary to effect ash removal, for relatively short periods, that alternate with longer periods, in each of which said plow makes a full revolution.

Dated this 5th day of July, 1929.

SVEN LEOPOLD BENGTSON.
